DESIGN FOR A SLIP

Sam Landau, New York, N. Y.

Application May 5, 1941, Serial No. 100,773

Term of patent 3½ years

To whom it may concern:

Be it known that I, Sam Landau, a citizen of the United States, residing at Manhattan, in the county of New York and State of New York, have invented a new, original, and ornamental Design for a Slip, of which the following is a specification, reference being had to the accompanying drawing, forming part thereof.

Figure 1 is a front view of a slip showing my new design.

Figure 2 is a rear view of the slip shown in Figure 1.

Figure 3 is an enlarged fragmentary front view of the embroidered design appearing in the upper portion of the slip shown in Figure 1.

The characteristic feature of my design resides in the combination of the specific embroidery arranged on the bust portion of the slip disclosed and the specific heart shaped edging and scalloping around the top, as shown.

I claim:

The ornamental design for a slip, substantially as shown and described.

SAM LANDAU.
